UNITED STATES PATENT OFFICE.

LEO DORFMAN, OF WILKINSBURG, PENNSYLVANIA, ASSIGNOR TO WESTINGHOUSE ELECTRIC & MANUFACTURING COMPANY, A CORPORATION OF PENNSYLVANIA.

SIGNALING SYSTEM.

Application filed August 3, 1921. Serial No. 489,448.

To all whom it may concern:

Be it known that I, LEO DORFMAN, a citizen of the United States, and a resident of Wilkinsburg, in the county of Allegheny and State of Pennsylvania, have invented a new and useful Improvement in Signaling Systems, of which the following is a specification.

My invention relates to antenna systems, and more particularly to sending systems coupled to a continuous-wave source of radio-frequency current.

An object of my invention is to provide means for controlling the power output of an antenna without making any physical change in the main-antenna circuit.

Another object of my invention is to provide means for controlling the effective capacity of a main antenna by the use of an auxiliary or control antenna.

A still further object of my invention is to change the amount of energy received by the antenna from the source of oscillations without materially varying the wavelength of the antenna output.

In sending messages where keys have been used to break the antenna circuit, arcing has been a serious problem. In other cases where the energy has been diverted into another circuit, the adjustment of the circuits to insure efficient operation has proved difficult.

In my system, I employ an antenna circuit coupled to a continuous-wave source of radio-frequency current. The antenna circuit is tuned to the frequency of the continuous-wave source. To prevent radiation I make use of an auxiliary antenna, preferably located beneath and substantially parallel to the main antenna, which is adapted to affect the main antenna to change its effective capacity. This I accomplish by connecting the auxiliary antenna to ground. The effective height of the main antenna is thereby varied. A key normally connects the auxiliary antenna to ground, and the main antenna operates to transmit messages only upon depression of the key.

The insertion of the auxiliary antenna between the main antenna and ground operates to greatly reduce the amount of energy received by the main-antenna circuit from the continuous-wave source of radio-frequency current.

The single figure of the drawings illus-

trates diagrammatically a sending system embodying the principles of my invention.

In the drawing, a main antenna 1 is connected, through a variable induction coil 2, to the ground. In this case, the distributed capacity of the antenna is presumed to be sufficient to furnish the necessary capacity for tuning the circuit to the desired frequency. Coupled to the induction coil 2 is a variable-induction coil 3, contained within a circuit having a variable condenser 4 and a continuous-wave source of radio-frequency alternations 5. The circuit within which the radio-frequency source 5 lies is tuned to resonance with the frequency of the source. The source of radio-frequency alternations may be any continuous-wave radio-frequency source, such as a thermionic oscillator, a high-frequency alternator, etc.

While I have shown such a system for coupling the main antenna circuit to the continuous-wave source of radio-frequency oscillations, it is to be understood that any method of coupling the circuits may be employed and that the particular system which I have illustrated is solely for the purpose of explanation.

Located below the main antenna 1 and substantially parallel thereto, is an auxiliary antenna 6. The ground lead from the auxiliary antenna 6 passes to a contact member 7 adapted to normally engage an arm 8 of a telegraphic key 9. The key 9 is pivoted and grounded at 11 and the other arm 12 of the key is held in an up position by means of a spring 13. Stops 14 and 15 limit the downward movement of the arms 8 and 12, respectively.

When the circuit of the auxiliary antenna 6 is open, the main antenna system, comprising the antenna 1 and the variable induction coil 2, is tuned to the frequency of the continuous-wave source 5. Therefore, under such conditions the antenna 1 radiates continuous-wave oscillations of the frequency of the source 5. However, since the auxiliary antenna 6 lies below the antenna 1 and substantially parallel thereto and is normally in circuit with the ground, the effective capacity of the antenna 1 is changed, and the main antenna system is, therefore, no longer in tune with the continuous-wave source 5. This greatly reduces the amount of energy received by the main antenna system, since but a small

change in the resonant frequency of the antenna system will make a large change in the amount of energy received.

Upon depressing the key 9, the arm 8 is raised and its contact with the contact member 7 is broken, thereby breaking the circuit between the auxiliary antenna 6 and the ground. The main antenna system is then resonant to the frequency of the continuous-wave source 5, and oscillations will be sent out while the key is depressed. Upon release of pressure on the key 9 the spring 13 causes the arm 8 of the key to make contact with contact member 7 in the lead 14 from the auxiliary antenna 6, and the auxiliary antenna is again connected to ground, thereby changing the resonant frequency of the main antenna system so that oscillations of the sending frequency are no longer emitted.

By employing an auxiliary antenna to change the effective capacity of the main antenna, I effect a great change in the amount of energy received from the continuous-wave source, whereby substantially no energy will be radiated while the auxiliary antenna is connected to ground, and, moreover, what small energy is radiated will have its frequency changed to some frequency other than the sending frequency. My system likewise permits the power output from an antenna to be controlled without altering or disturbing the main-antenna circuit.

35 Since I have not shown all of the possible modifications of my invention which could be conceived by one skilled in the art, I desire that my invention shall be limited solely by the prior art and the scope of the 40 appended claims.

I claim as my invention:

1. A method of changing the resonant frequency of an antenna which consists in changing the effective height of the antenna 45 leaving the physical height unaltered.

2. A method of changing the resonant frequency of an antenna which consists in connecting a neighboring antenna to ground and thereby changing the effective height 50 of the first antenna.

3. A method of changing the capacity of a main antenna comprising locating an auxiliary antenna below the main antenna and connecting the auxiliary antenna to the 55 ground.

4. A method of sending radio messages comprising the steps of tuning a main sending antenna to a desired frequency, locating an auxiliary antenna below the main antenna, connecting said auxiliary antenna to the ground and making and breaking said connection in accordance with the message.

5. A variable antenna comprising a main antenna, an auxiliary antenna located below 60 the main antenna, and switching means as-

sociated with the auxiliary antenna for making and breaking a connection to ground, whereby the capacity of the main antenna may be varied.

6. A sending system comprising a continuous-wave source of radio-frequency oscillations, an antenna tuned to the frequency of the source and coupled thereto, and means for varying the effective height of the antenna leaving the physical height unaltered. 75

7. A sending system comprising a continuous-source of radio-frequency oscillations, a main antenna tuned to the same frequency as the source and coupled thereto, a grounded auxiliary-antenna circuit including an auxiliary antenna below said main antenna and a key in the auxiliary-antenna circuit to make and break the connection to ground, whereby the effective capacity of the main antenna may be varied. 80 85

8. A method of sending radio signals comprising the steps of tuning an antenna to the sending frequency, coupling it to a continuous-wave source of the sending frequency, locating an auxiliary antenna within influencing distance of the first antenna and varying the energy output of the antenna by changing the connections of the auxiliary antenna and thereby changing the effective capacity of the main antenna. 90 95

9. The method of modulating the current in an antenna circuit, which consists in connecting the antenna to ground through a circuit having greater capacity than the normal capacity of the antenna with respect to ground. 100

10. The combination with a tuned antenna circuit, of an auxiliary circuit connecting the antenna to ground, said auxiliary circuit having greater capacity than the normal capacity of the antenna with respect to ground, and modulating means in said auxiliary circuit. 105

11. The combination with a tuned antenna circuit, of an auxiliary circuit connecting said antenna to ground, said auxiliary circuit having capacitive impedance, and modulating means in said auxiliary circuit. 110

12. In a radio sending system, a flat-top antenna, means for causing the same to radiate, and means for checking said radiation, comprising a second flat-top antenna the top of which is below and electrostatically coupled to the top of the first-mentioned antenna. 115

13. In combination, two flat-top antennæ, a source of undamped radio-frequency energy in one of said antennæ and a switch in the other, the said antenna being electrostatically coupled and the frequency of said source being that for which its antenna is resonant when the switch is open. 120 125

14. A means for altering the period of a flat-topped antenna, comprising a horizontal 130

conducting body electrostatically coupled to which is of the same order of magnitude the top of said antenna, and a separable connection between said body and the ground.

10

15. A means for altering the period of a flat-topped antenna, comprising a horizontal conducting body electrostatically coupled to the top of said antenna and the area of

In testimony whereof, I have hereunto subscribed my name this 27th day of July, 1921.

LEO DORFMAN.
